Specification of Letters Patent.

Patented Jan. 27, 1914.

Application filed March 13, 1911. Serial No. 614,052.

To all whom it may concern:

Be it known that I, OSCAR ROESEN, a citizen of the United States, residing at New York, county of New York, and State of New York, have invented certain new and useful Improvements in Multicolor-Printing Presses, fully described and represented in the following specification and the accompanying drawings, forming a part of the same.

The object of the present invention is to provide an improved multicolor printing press, by which the required number of colors shall be printed with the desired interval of time between the color impressions to let the ink of one color set before the next color is printed, and which shall be simple and compact in construction, and more satisfactory in operation than previous presses of this class. This result is secured by the use of an impression cylinder with a series of printing cylinders corresponding to the number of colors to be printed, and operating the impression and printing cylinders so that the sheet is printed upon by the successive printing cylinders during different rotations of the impression cylinder, the cylinder making one or more rotations between successive impressions on a sheet, and the printing cylinders are withdrawn from printing contact with the sheet except on that rotation of the impression cylinder during which they print the sheet. The impression cylinder is preferably divided into impression surfaces or sections for carrying a plurality of sheets, which impression surfaces or sections are provided with sheet holding devices operating to hold the sheet through the successive impressions and then release the printed sheets for delivery. The printing cylinders are preferably transfer cylinders printing by transfer from a plate cylinder, as usual in transfer printing, so as to avoid make ready, but the broader features of the invention may be used with any other suitable printing method. An offset web device or other drying means is preferably used to blot and dry the colors between impressions. The sheets are preferably fed to the successive impression surfaces of the impression cylinder on successive rotations of the impression cylinder and delivered therefrom on successive rotations, important advantages in the operation of the press being thus secured, but the sheets may be fed to all impression surfaces on one rotation

and delivered on another rotation after the printing of all the sheets is completed within the broader features of the invention.

In the accompanying drawings forming a part of this specification there are shown for purpose of illustration transfer presses embodying all the features of the invention in preferred forms, and these constructions will now be described in detail, and the features forming the invention then specifically pointed out in the claims.

In the drawing:—Figure 1 is a diagrammatic vertical section of a press for printing four colors, with an impression cylinder having three impression surfaces or sections. Fig. 2 is an end elevation looking to the left in Fig. 1, on a larger scale, partly broken away to omit the sheet gripper operating cam and devices. Fig. 3 is a detail side elevation of the sheet gripper operating devices. Fig. 4 is a detail plan view of the same. Fig. 5 is a view similar to Fig. 1 showing a press for printing four colors with an impression cylinder having four impression surfaces or sections and arranged for feeding and delivering the sheets from the successive surfaces on the same rotation.

Referring now especially to the construction shown in Figs. 1 to 3, A is the impression cylinder having three impression surfaces or sections, 1, 2, 3, and B', B'', B'', B'' the four color printing cylinders, each printing cylinder having its corresponding plate cylinder C', C'', C'', C''. The printing cylinders in the form shown are provided with suitable transfer surfaces, such as rubber blankets 10, stretched thereon, and the plate cylinders C' carry the usual aluminum or similar plates 11 for planographic printing and the plate cylinders are shown as having the usual dampening and inking mechanisms 12, 13 which may be of any suitable form. Each of the impression surfaces or sections 1, 2, 3, is provided with a set of sheet grippers a, to which the sheets are fed from feed boards D, and from which the sheets are delivered to delivery roll E and fly F of any common or suitable form. Between the printing cylinder B'' and the delivery cylinder E is an offset web device having the usual offset rolls G, G' and offset web H to aid in the drying process but other drying devices may be used for this purpose, such as hot air, chemicals, cold air, powder, etc., or the press may be used without such drying devices.

In the form of press shown and now being described, the impression cylinder, printing cylinders, and plate cylinders are geared together in train, so as to rotate continuously at the same surface speed, with the impression cylinder making one rotation between impressions on a sheet, and the plate cylinders are moved toward and away from the impression cylinder to bring them into and out of printing contact with the impression surfaces and toward and from the plate cylinders to receive an impression for transfer, without stopping any of the cylinders. For this purpose the printing cylinders B', B², B³, B⁴ are mounted in eccentric bearings 13, which eccentrics are shifted by links 16 connected to arms 17 on rock shafts 18 operated by cam arms 19 from cams 20 mounted on shaft 21 of the impression cylinder. These cams, in the construction now being described, are formed to make one rotation to each one and one third rotation of the impression cylinder, and for each cam to hold its printing cylinder in printing contact with an impression surface of the impression cylinder during printing or about one third of the rotation of the impression cylinder, then to move the printing cylinder away from and out of printing contact with the impression cylinder but not into contact with its plate cylinder and hold it in such intermediate position during somewhat more than one half of the impression cylinder rotation, then to move the printing cylinder into contact with the plate cylinder for receiving an impression, and then to return the printing cylinder into printing contact with the impression cylinder for printing another sheet on the next impression surface on the next rotation of the impression cylinder. The cams 20 are shown as formed in pairs on opposite sides of cam disks 22 mounted on the shaft 21 at opposite sides of the press frame, and these cam disks 22 are driven by suitable gearing to make one rotation to each one and one third rotation of the impression cylinder A so that each printing cylinder co-acts at successive rotations with the successive impression surfaces 1, 2, 3. As shown, the impression cylinder A is driven from main driving shaft 23 by a train of gears 24, the last gear engaging with gear 25 on impression shaft 21, and the cam disk 22 on the gear side of the press is driven from the same shaft through the first two gears 24, gear 26 on the shaft of the second gear 24, intermediates 27 and gear 28 on the cam disk, and the cam disk on the opposite side of the press by a similar train of gears, these gears being proportioned so as to secure the desired timing of the cam disks relatively to the impression cylinder, as shown in Fig. 1.

The sheet grippers *a* in the construction now being described, are operated success-

sively on different rotations of the impression cylinder, each gripper being operated to take a sheet, hold it during four rotations of the impression cylinder for printing with the four colors and then deliver the printed sheet. For this operation any suitable gripper operating devices may be used so as to operate the cylinder grippers *a*, sheet stops *b* and sheet grippers *c* of delivery roll *E* to secure the proper receipt of sheets by the cylinder *A* and their proper transfer to roll *E* for delivery. In the construction illustrated, a single cam disk *I* is used which carries a feeding cam *d* and delivery cam *e*, this cam disk *I* being geared to make one rotation to each one and one-third rotation of the impression cylinder *A*, and the cams *d*, *e* thus being operated to open the grippers *a* to deliver a printed sheet and take a new sheet upon each impression surface 1, 2, 3, 85 at each fourth rotation of the surface, and to thus operate the grippers of the three surfaces on successive rotations of the cam disk. The feeding cam *d* operates each of the grippers *a* and sheet stops *b* as follows:—The gripper shaft 29, which is spring pressed as usual to close the grippers *a*, carries an arm 30 having a slot in position to receive the inner end of a pin 31 mounted to slide in the frame and having at its outer end a slotted block 32 engaged by cam 33 carried by rock sleeve 34 mounted on a stud in the frame and rocked to move pin 31 in and out by cam *d* through arm 35 on sleeve 34 carrying roll 4 engaging cam *d*. Another sleeve 34^a on the stud carrying sleeve 34 has arm 36, the outer end of which carries roll 4^a and is connected by link 37 to rock arm 38 on shaft 39 carrying sheet stops *b*. Thus cam *d* by engagement with roll 4 operates cam 33 at each rotation of the cam disk *I* to move the pin 31 inward into position to engage the slot in arm 30 on gripper shaft 29 on one of the impression surfaces 1, 2, 3 to close the grippers to seize a sheet and by engagement with roll 4^a on arm 36 raises the sheet stops *b* for feeding a sheet from feed-board *D* on each rotation of the cam disk *I*. The grippers *a* are opened to deliver a sheet as follows:—The slot in arm 110 30 on gripper shaft 29 engages the inner end of the pin 40 similar to pin 31 and moved in and out by cam 41 on rock sleeve 42 engaging a slot in block 43 on pin 40, sleeve 42 being actuated by arm 44 carrying roll 5 engaging cam *e*. Sleeve 42 carries also an arm 45 geared with arm 46 on rock shaft 47 mounted in the frame, which rock shaft carries cam 48 mounted to engage rock arm 49 on shaft 50 of grippers *c* of delivery roll *E*, when the cam 48 is rocked outward by arm 46. The cam *e* thus moves pin 40 inward on each rotation of the cam *e* to engage arm 30 and rock shaft 29 to open the grippers *a* of one of the impression sur- 130

faces 1, 2, 3 for delivery of a printed sheet, and at the same time through arms 45, 46 rocks cam 48 into position to open the grippers *c* to receive the sheet from grippers *a*. The gripper mechanism is of the now well-known tumbler type, and the form of this mechanism is not essential to the invention, so that a brief description of the operation will suffice. Referring to Fig. 3, the shaft 29 is shown in the position in which the grippers have been closed to seize a sheet on feed board. At the conclusion of the printing operation, the pin 40 is pushed into the path of the slotted block 32 on arm 30 by the cam *e*, arm 44 and cam 41, and engages with the inner end of the slot, that is, the one next the cylinder center. As the pin 40 is nearer the center of the cylinder than the shaft 29, its effect is to rotate the shaft 29, and consequently the sheet grippers, through a predetermined angle, and so as to open the grippers and release the sheet. In this operation the shaft 29 is rocked so that the outer end of the slot in block 32, that is, the end 25 away from the cylinder center, is ahead of shaft 29. When the shaft 29 reaches the sheet-taking position, the leading and outer end of the slot in arm 32 engages the pin 31 and, as pin 31 is farther from the cylinder center than shaft 29, the continued forward motion of the cylinder A rotates the shaft 29 and grippers *c* of the cylinder through the same angle that sheet-releasing pin 40 has turned them, thus restoring the parts to the 35 position shown in Fig. 3, and seizing the sheet.

The operation of the press shown in Figs. 1 to 3, and above described will be understood from a brief description. The impression surfaces 1, 2, 3 take sheets on successive rotations of the impression cylinder, and each impression surface holds its sheet so that it is printed with one color on each of four successive rotations of the impression cylinder, being thus printed successively by printing cylinders B', B², B³, B⁴, the printing cylinders being held out of printing contact with each surface during the rotation on which they do not print on such surface, and on the fourth rotation the impression surface delivers its printed sheet to delivery roll E, and then at the beginning of the fifth rotation takes another sheet from feed board D for printing. Sheets are thus taken on the impression surfaces 1, 2, 3, printed by the respective printing cylinders B', B², B³, B⁴ on successive rotations of the impression cylinder, and delivered, so that three sheets are thus printed and delivered at each four rotations of the impression cylinder, there being a full rotation between the printing of successive colors on each impression surface. The cams operating to raise and lower the printing cylinders, and to operate the sheet grippers

make three rotations to each four rotations of the impression cylinder, so that they are in proper position to operate in connection with each of the three impression surfaces on each fourth rotation of such surface.

The construction above described, in which three impression surfaces are used, is preferred, when four colors are to be printed, this arrangement providing for printing sheets on all the impression surfaces at every rotation of the impression cylinder, while at the same time securing a compact construction with a comparatively small impression cylinder. If five colors are to be printed, the preferred arrangement, for the same reasons, will be four impression surfaces, and in general a number of impression surfaces one less than the number of colors to be printed. It will be understood, however, that any number of impression surfaces may be used with any number of printing cylinders, suitable cams and timing of the various parts being used to secure the desired operation. Thus, if it be desired to increase the number of impression surfaces, in order to give more time for setting the colors between impressions, or for other reasons, the number of impression surfaces may be increased as desired, the number of sheets taken and delivered in a rotation cycle of the impression cylinder, varying according to the number of impression surfaces used and colors printed. With the construction illustrated, employing a simple rotating cam disk for the grippers and printing cylinders, the rotation in a cycle will be one more than the number of impression surfaces used. Thus with four impression surfaces and printing four colors, four sheets will be delivered to each five rotations, and with five impression surfaces printing four colors, five sheets to six rotations. In some cases, it may be desired to reduce the number of impression surfaces below three, which will reduce the size of the press, but, of course, only two sheets or one sheet will be taken and delivered to each four rotations of the impression cylinder, as the number of impression surfaces are reduced to two or one, suitable cam movements being used for such operation. If more time between colors be desired, which may be the case where a small cylinder is used, the press may readily be constructed for two or more rotations between colors, instead of only one rotation, as shown and above described, the operating devices being changed accordingly.

The construction and operation above described, in which the successive impression surfaces take and deliver sheets on different rotations of the impression cylinder, have many advantages over a construction in which the sheets are taken on all the impression surfaces on the same rotation and

delivered on the same rotation, especially in that the sheet feeding mechanism operates more slowly and regularly, the gripper motion is simpler as only one gripper is operated at each rotation, a very simple transfer printing movement may be used, and the plate cylinders and inking motions rotate several revolutions to each printing, so that a much simpler and more efficient inking motion is possible. The press may be constructed, however, so that the impression surfaces take sheets successively on the same rotation, and deliver sheets successively on another rotation, within the invention considered broadly, and such a construction is illustrated in Fig. 5. Referring to the construction shown in Fig. 5, the impression cylinder has four impression surfaces 1, 2, 3, 4, on which sheets are taken successively by sheet grippers *a* on one rotation, and from which the printed sheets are delivered successively on the fourth rotation thereafter. The cam mechanism for actuating grippers *a*, *c*, and sheet stops *b* will be arranged in any suitable manner to secure this result, the single cam disk mechanism of Figs. 1 to 4, if used, being geared to make one rotation to four rotations of the impression cylinder. The printing cylinders *B'*, *B²*, *B³*, *B⁴* will be actuated so that each printing cylinder is in contact with and prints upon a sheet on each of the four impression surfaces during one rotation of the impression cylinder, and then is raised out of printing contact with the impression cylinder during three rotations of the cylinder and returned to printing position on the next or fifth rotation to print another sheet on each of the impression surfaces, the printing cylinders *B'*, *B²*, *B³*, *B⁴*, being thus actuated successively so as to print a sheet on successive rotations of the impression cylinder. The cams and connections for moving the printing cylinders toward and from the impression cylinder are similar to those of Figs. 1 to 4, except that the cams are timed to make one rotation to each four rotations of the impression cylinder and constructed to hold the printing cylinders in printing contact with the impression cylinders during one-fourth of their rotation and out of printing contact with the cylinders during three-fourths of their rotation. This is illustrated in connection with the cam for moving printing cylinder *B'* in which the cam 51 for this printing cylinder is shown with its gearing arranged to drive the cam at a ratio of one to four relatively to the impression cylinder, the gearing having the same references as in Figs. 1 to 4, and being the same, except as to the proportionate sizes of the gears. The printing cylinders *B'*, *B²*, *B³*, *B⁴* obviously will be geared to make four rotations to each rotation of the impression cylinder so as to print on each of the four impression

surfaces, and the cams moving the printing cylinders therefore will hold the printing cylinders out of printing contact with the impression cylinder during twelve rotations of the printing cylinders, and during these twelve rotations no transfer is made from the plate cylinders *C'*, *C²*, *C³*, *C⁴* to the printing cylinders, but the plate cylinders are in contact with their respective printing cylinders and transfer thereto during the four printing rotations of the printing cylinders, and then are separated from the printing cylinders for twelve rotations. To secure this result the plate cylinders are mounted in eccentric bearings 6, and are operated by extensions 7 of the plate cylinder operating links 16, so as to move the plate cylinders and their inking and moistening mechanisms away from the printing cylinders on the outward movement of the printing cylinders and into contact with the printing cylinders again on the inward movement of the latter. The plate cylinders, therefore, are moistened and inked during twelve rotations without transfer and then transfer during four successive rotations. The relative circumferential positions of the printing and plate cylinders are clearly shown in Fig. 5 and their operation will be understood without further description.

The operation of the construction shown in Fig. 5 will be understood from the above without further description, it being understood that the impression cylinder *A* takes four sheets on one rotation of the cylinder, each of these sheets is printed by cylinder *B'* on the first rotation, cylinder *B²* on the second rotation, cylinder *B³* on the third rotation and cylinder *B⁴* on the fourth rotation, and the sheets are then delivered on the fourth rotation printed in four colors, and this operation repeated on each four rotations. In this construction it will be understood, as in the construction previously described, that the press may be arranged for two or more rotations between the printing of successive colors if more time between the successive impressions be desired, and that the number of colors and impression surfaces may be varied as desired.

The invention enables the production of a very simple and compact printing multicolor press in which any desired number of colors may be printed, and which, with a suitable number of impression surfaces, secures high capacity while providing the time required for setting of colors between impressions. A very efficient action of the press is secured, the sheets being held by the same grippers through all the printing operations, thus securing the best conditions for absolute register, and the time between impressions from the same printing cylinder giving ample time for the best inking

results on the plate cylinders and the use of simple inking mechanism. The use of a transfer or planographic process for printing avoids all make ready and secures the proper conditions for printing each color on the sheet.

It will be understood that the invention is not limited to the transfer printing process, although this is preferred, especially in 10 the arrangement illustrated in Figs. 1 to 4, nor to the particular construction of rotary press shown, but that other printing processes may be used and the printing cylinders may be arranged on the rotary stop 15 cylinder principle, stopping each pair of cylinders when it has printed, instead of using continuously rotating printing cylinders, and that the broader features of the invention are applicable also with impression 20 and printing surfaces not having a rotary movement.

What I claim is:—

1. In a multiple impression printing press, the combination with a series of 25 printing surfaces, of an impression surface moving over the printing surfaces, and means for moving the impression surface and each of the printing surfaces toward and from each other for printing a sheet 30 on the impression surface from the printing surfaces successively on different movements of the impression surface over the series of printing surfaces.

2. In a multiple impression printing 35 press, the combination with a series of printing surfaces and an impression surface moving over the printing surfaces, of means for moving each of the printing surfaces into and out of printing contact with 40 the impression surface independently of the other printing surfaces to print a sheet on the impression surface from the successive printing surfaces on different movements of the impression surface over the series of 45 printing surfaces.

3. In a multiple impression printing press, the combination with a rotating impression surface provided with sheet holding devices and a series of printing cylinders co-acting 50 with said impression surface, of means for moving each of the printing cylinders toward and away from the impression surface to bring it into and out of printing contact with the impression surface for printing a 55 sheet on the impression surface by the successive printing cylinders on different rotations of the impression surface, and means for operating the sheet holding devices to hold the sheet on the impression surface 60 during its successive printing rotations for printing the sheet by the series of printing cylinders.

4. In a multiple impression printing press, the combination with an impression cylinder having a plurality of impression surfaces, of 65 a series of printing cylinders co-acting with said impression surfaces, and means for moving each of said printing cylinders toward and away from the impression cylinder to bring it into and out of printing 70 contact with the successive printing surfaces for printing a sheet on the same impression surface by the successive printing cylinders on different rotations of the impression cylinder, and sheet holding devices 75 arranged to hold the sheets during the rotations of the impression cylinder for printing a sheet by the series of printing cylinders.

5. In a multiple impression printing press, the combination with an impression cylinder having a plurality of impression surfaces, of 80 a series of transfer printing cylinders co-acting with the impression surfaces and plate cylinders co-acting with the transfer cylinders, means for moving the transfer 85 cylinders away from the impression cylinder and into contact with the plate cylinders for receiving the transfer impression and toward the impression cylinder for printing sheets on successive impression surfaces on different 90 rotations of the impression cylinder, and sheet holding devices arranged to hold the sheets on the same impression surface during the rotations of the impression cylinder for printing a sheet by the series of printing 95 cylinders.

6. In a multiple impression printing press, the combination with an impression cylinder having a plurality of impression surfaces, of 100 a series of printing cylinders co-acting with said impression surfaces, means for moving each of said printing cylinders toward and away from the impression cylinder to bring it into and out of printing contact with the successive printing surfaces for printing a 105 sheet on the same impression surface by the successive printing cylinders on different rotations of the impression cylinder, sheet holding devices for each impression surface, and means for actuating the sheet holding 110 devices to take and deliver sheets by the successive printing surfaces on successive rotations of the impression cylinder and to hold the sheets during the rotations of the impression cylinder for printing by the series 115 of printing cylinders.

In testimony whereof, I have hereunto set my hand, in the presence of two subscribing witnesses.

OSCAR ROESEN.
